UNITED STATES PATENT OFFICE.

JOHN S. MOORE AND WILLIAM C. GLASS, OF ATLANTA, GEORGIA.

RAILWAY-TRAIN STOP.

1,323,991.

Specification of Letters Patent.

Patented Dec. 2, 1919.

Application filed February 10, 1919. Serial No. 276,122.

To all whom it may concern:

Be it known that we, JOHN S. MOORE and WILLIAM C. GLASS, citizens of the United States, residing at Atlanta, in the county of Fulton and State of Georgia, have invented 5 certain new and useful Improvements in Railway-Train Stops, of which the following is a specification, reference being had to the accompanying drawings.

10 This invention relates to mechanism for automatically stopping railway trains, and particularly to mechanism of that class wherein the train is stopped by releasing the air in the train pipe, as by opening a 15 venting cock.

The general object of this invention is to provide means located along the track and operating in conjunction with the switch stand or block signal stand for this purpose.

20 A further object is to provide a construction of this character which will render it impossible for a train to proceed past a red or danger signal, even though the engineer fails to see the signal.

25 A further object is to provide a mechanism which is very simple, has few parts, and which may be readily connected to the ordinary block signals now in use, and in this connection to provide a construction of

30 this character which may be fastened to the rails at any desired point by means of clamps so that the apparatus may be readily put in place, adjusted, or shifted, as necessity may require, these clamps being so 35 formed that the parts will be held rigidly in position to the rails and will not get out of position, as does mechanism of like general character which is mounted upon the wooden cross ties of the track.

40 Other objects and advantages of our construction will appear in the following specification.

Figure 1 is a top plan view of a railway track and a portion of a locomotive with 45 vent valve and the track operated mechanism therefor;

Fig. 2 is a perspective view of the vent valve;

Fig. 3 is a fragmentary perspective view 50 showing an arrangement of signal and stop member coacting therewith;

Fig. 4 is a transverse sectional view showing the manner in which the stop member is connected to the rail;

55 Fig. 5 is a perspective view showing another form of train stop;

Fig. 6 is a transverse sectional view through the rail clamp and the train stop shown in Fig. 5;

Fig. 7 is a transverse sectional view 60 through the rail showing the bracket 26 and supported parts; and

Fig. 8 is a top plan view of a turn out 65 and showing the arrangement of the train stop in connection therewith.

In the accompanying drawings, we have 70 shown two forms of automatic stop mechanism, one of these forms being shown in Figs. 1 to 4. Both of these forms are alike as regards the vent valves on the locomotive, 75

but differ slightly with relation to the track mechanism. Inasmuch as the vent valve and its connections on the locomotive is the same in both cases, we will first describe this mechanism, and in Fig. 1, it will be seen 80 that the pony truck of the locomotive carries a train line pipe 10 which is provided with a vent valve 11 which, when turned in one position, releases the air within the train line pipe and, of course, causes the application of the brakes in the usual and well known manner. This cock or valve is provided with a stem to which is attached an arm 12, and pivotally mounted upon the extremity of this arm is a section of the arm 85

13 which is pivoted to the main body of the arm 12, at 14. The arm 13 is formed to provide a stop flange or lug 15 which limits the movement of the arm section 13 with relation to the arm section 12 in one direction, but permits the independent movement 90 of the arm section 13 in the other direction. A spring 16 urges the arm section 13 into alignment with the arm section 12. When the arm section 13 is struck by a train coming in one direction, as from the right in Fig. 1, the two arm sections will move together to open the vent valve, but when the train backs up or moves reversely, that is from the left, in Fig. 1, then the arm section 95 13 will rock upon its pivot and the arm section 12 will not be affected, nor will the valve be opened.

It will be understood that the vent valve may be disposed on any part of the engine or tender, but is disposed preferably on the pony truck and so mounted as to keep the same distance from the rail, this valve or its arm clearing the rail by about two inches and the body of the valve being connected to the main train line pipe by an 105 air hose or other suitable connection. The valve is, of course, so substantially con- 110

structed that the handle will not break off from the valve when struck by the track stop lever, even when the train is going at a high rate of speed.

5 In Figs. 3 to 4, we show one form of our invention, and in these figures, 17 designates a pair of brackets, these brackets being slotted at one end so as to embrace the lower flange of the rail A and fit tightly thereon. Each bracket is held to the rail by means of a bolt 18 having a hook at one end to embrace the opposite edge of the base flange, this bolt passing through the bracket and being provided with a nut 19 whereby the bracket may be forced firmly onto the rail and held rigidly thereon. Passing through these brackets and extending parallel to the rail A, is a rock shaft 20 which, at one end, is provided with a 10 downwardly extending arm 21, this arm being pivotally connected to a transversely extending link 22, in turn pivotally connected to a movable element 23 forming part of or shifted by any ordinary block signal 15 apparatus or switch mechanism. This mechanism which we have designated generally B, forms no part of our mechanism and is adapted to be used in connection with train order boards, switch targets, electrical 20 block boards, or in all the signal and switch mechanism at present used or forming part of the equipment of railway systems of this country. Disposed on the other 25 end of the shaft 20 is an upwardly extending arm 24. When the signal mechanism B is set at "danger" it will, through the link 22, rock the shaft 20 and this will shift the stop arm 24 into such position that it will 30 strike the arm section 13 of the vent valve on the engine, causing, as before described, the application of the brakes. Normally, however, and when the signal is not at "danger", this stop arm 24 is disposed out 35 of the path of movement of the arm section 13 and will, therefore, not affect the vent valve.

In Figs. 5 to 7, we show another form of the mechanism which operates on the same general principle as the one before described, but differs therefrom in details. In 40 this construction, one of the brackets 17 carries upon it the upwardly extending stop arm 25 which, however, is pivoted upon the clamping bolt 18 and oscillates parallel to 45 the rail A instead of transversely thereto, as in the first case. Pivotally mounted upon a bracket 26 clamped to the rail A, is a bell crank lever 27 which is disposed beneath the rail and between the ties and has one arm 50 extending inward of the rail A, this arm being connected to the stop arm 25 by means of a link 28 pivoted to the stop arm 25 and preferably embracing it. The long arm of 55 the bell crank lever is connected by a link 60 29 to the block signal mechanism B in any

suitable manner. Thus, when this block signal mechanism is set at "danger", the bell crank lever 27 will be rocked to shift the stop arm 25 to a vertical position where it will come in contact with the arm section 70 13 of the vent valve mechanism. When, however, the signal is set at "safety"; or at "caution", the arm 25 will be depressed sufficiently so as to pass beneath the arm section 13 or vent valve and does not affect it. 75

As soon as the vent valve is opened by having its arms struck by the stop arms 24 or 25, the train will come to a stop and it cannot be started again until the brakes are released. This necessitates the engineer 80 descending from his cab and manually closing the vent valve by shifting the arm sections 12 and 13 to their outwardly projected positions. Of course, after the engine has passed the automatic stop, the engineer can back the train without affecting the vent valve, for the reason that the section 13 will yield to permit it to pass the stop arm on the track. 85

It is, of course, necessary that where signals are used adjacent to a siding, that a train will not be stopped if it leaves the main track and passes onto the siding, but that a train passing the junction of the siding with the main track onto the main track 90 should be stopped. We have illustrated in Fig. 8 such an arrangement wherein the stop arm 24 is disposed inward of the switch points C which lead onto the siding D. Of course, this arrangement is the same at both 95 ends of that section of track which extends parallel to the siding. 100

It is likewise evident that at stations where provision is made for stopping a train to receive train orders, but where ordinarily 105 the train does not stop, it is necessary to provide means whereby the engine tender and the fore part of the train shall move beyond the station or office, and to that end we dispose the stop arms 24 (or 25) beyond 110 the station relative to the direction in which the train is moving such a distance beyond as to permit the passenger coaches stopping opposite the station. This involves, of course, a relatively long rock shaft 20 or 115 relatively long link 28 or a series of these links 28 operatively connected to each other and to levers for communicating the movement of one link to another. 120

It will be seen that the mechanism here-with described is extremely simple, that there are no springs to weaken, that there are very few parts, and that these parts are not of the sort which are liable to be clogged by snow or to be frozen up. It will 125 also be seen that the cost of installation is very small, and that the mechanism may be readily applied at small cost to the systems already in use, and readily connected up with the ordinary or usual train order 130

boards, block signals, whether electrically or mechanically actuated, or to switch stands.

In the drawings we have illustrated an ordinary form of signal wherein the signal proper is mounted upon a rotatable standard for rotation in a horizontal plane, but it is to be understood that this showing is purely illustrative and that this signal B wherever used symbolizes or indicates a signal of any character where there is a shiftable element by which the stop member 25 may be shifted.

We claim:—

The combination with a railway rail of a plurality of brackets detachably engaged with the rail, a bell crank lever pivoted to the bottom surface of one of said brackets,

a stop arm pivoted to one side of another of said brackets, a rod pivotally connected at one end to the stop arm above the supporting bracket thereof, the other end of said rod being pivotally connected to one end of the bell crank lever, and a signal mechanism operatively connected to the other end of the bell crank lever.

In testimony whereof we hereunto affix our signatures in the presence of two witnesses.

JOHN S. MOORE,
WILLIAM C. GLASS.
